FRANS JOHAN HENRIK RUSTIGE, OF LILLA ESSINGEN, STOCKHOLM, SWEDEN.

FIRE-EXTINGUISHING APPARATUS.

1,184,776.

Specification of Letters Patent.

Patented May 30, 1916.

Application filed October 28, 1913. Serial No. 797,802.

To all whom it may concern:

Be it known that I, FRANS JOHAN HENRIK RUSTIGE, a subject of the King of Sweden, residing at Lilla Essingen, Stockholm, Sweden, have invented new and useful Improvements Relating to Fire-Extinguishing Apparatus, of which the following is a specification.

Devices for automatic fire extinguishing are known which consist of a pipe system connected to a receptacle for liquid carbon dioxide and provided with discharge openings closed by a readily fusible substance which is melted by fire arising adjacent to the opening and thereby discharge carbon dioxide which chokes the fire. If, however, the pipe system, as generally is preferred in practice, is arranged at the top of the rooms or chambers to be protected, it may happen that the discharged carbon dioxide, although heavy, does not sink to the bottom of the room or chamber, where the fire usually begins, especially in the case of coal bunkers, but the gas will be retained at the top on account of the air currents caused by the fire and thus be inactive during a considerable time, or until a sufficient quantity of carbon dioxide has escaped to fill the room. The purpose of the present invention is to avoid the said inconvenience, and this is accomplished by combining with the pipe system arranged at the top of the chambers branch pipes which lead to or adjacent to the bottom of the rooms, the sealing pieces of readily fusible metal then being arranged at the branching points, *i. e.* at the top of the room where they are most readily available for the action of a rising temperature in the room. By this arrangement, when fire arises for instance at the bottom of a coal bunker, the carbon dioxide which is emitted from an opening near the fire place will be led to the bottom of the bunker through the branch pipe and will thus have better access to the fire than if it were emitted at the top.

However, if fire is also spread to the upper parts of the bunker or room, the carbon dioxide will soon choke it as it rises on account of the draft caused by the fire.

In the accompanying drawing, a ship provided with a fire extinguishing system according to the present invention is shown in a longitudinal vertical section.

1 is a receptacle for liquid carbon dioxide, from which a pipe leads to a system of pipes 55 distributed along the compartments of the ship. The said pipes 2 run at the top of the compartments, rooms or bunkers and are provided with valves 5 opening by the fusion of a metal piece. From said valves, branch 60 pipes 3 run down through the compartments so as to have their mouths 4 near the bottom thereof.

Having now particularly described the nature of my invention and the manner of its 65 operation, what I claim is:

An apparatus for automatically extinguishing fire by means of carbon dioxide, comprising a source of supply of liquid carbon dioxide, a system of substantially horizontal pipes connected with said source and arranged at the top of the rooms to be protected, normally closed valves situated in said pipes at suitable points, thermostatic controlling means for each valve carried directly thereby, and stationary branch pipes leading from the respective valves down to a level substantially at the bottom of the rooms, the lower end of each branch pipe being open and disposed directly beneath the 80 corresponding valve and its thermostatic means.

In testimony whereof I have signed my name to this specification in the presence of two subscribing witnesses.

FRANS JOHAN HENRIK RUSTIGE.
